(57) **CLAIM**

The ornamental design for a therapeutic back pad, as shown and described.

DESCRIPTION

FIG. 1 illustrates a perspective view of a therapeutic back pad;

FIG. 2 illustrates a front view of the therapeutic back pad thereof;

FIG. 3 illustrates a back view of the therapeutic back pad thereof;

FIG. 4 illustrates a left side view of the therapeutic back pad thereof;

FIG. 5 illustrates a right side view of the therapeutic back pad thereof;

FIG. 6 illustrates a top view of the therapeutic back pad thereof;

FIG. 7 illustrates a bottom view of the therapeutic back pad thereof; and,

FIG. 8 is a front view of the therapeutic back pad in use. The broken lines shown in FIGS. 1–8 illustrate portions of the therapeutic back pad that form no part of the claimed design. The additional broken lines in FIG. 8 illustrate environment and form no part of the claim.

The therapeutic back pad of the present invention is used by the user for relief of the back pain.

1 Claim, 6 Drawing Sheets
